Primary Examiner — Richard Edgar*Assistant Examiner* — Nader Abadir(74) *Attorney, Agent, or Firm* — Larry K. Roberts(57) **CLAIM**

The ornamental design for a travel mug as shown and described.

DESCRIPTION

FIG. 1 is an isometric view of a travel mug showing the new design;

FIG. 2 is a back elevation view thereof;

FIG. 3 is a front elevation view thereof;

FIG. 4 is a right side elevation view thereof;

FIG. 5 is a left side elevation view;

FIG. 6 is a top view thereof; and,

FIG. 7 is a bottom view thereof.

The broken lines depict portions of the travel mug that form no part of the claim.
